UNITED STATES PATENT OFFICE.

WILLIAM BOEKEL AND JULIUS BOEKEL, OF PHILADELPHIA,
PENNSYLVANIA.

DESIGN FOR A NEBULIZER-SUPPORT.

SPECIFICATION forming part of Design No. 36,000, dated August 12, 1902.

Application filed April 12, 1902. Serial No. 102,683. Term of patent 14 years.

To all whom it may concern:

Be it known that we, WILLIAM BOEKEL and JULIUS BOEKEL, citizens of the United States, residing at Philadelphia, in the county of 5 Philadelphia and State of Pennsylvania, have invented a certain new and original and ornamental Design for a Nebulizer-Support; and we do hereby declare the following to be a full, clear, and exact description of the invention, 10 such as will enable others skilled in the art to which it appertains to make and use the same.

This invention relates to a design for a nebulizer-support consisting of an ornamental base resting on decorated legs, an upright columnar 15 tank of smooth cylindrical form with convex top and a circular table mounted thereon, said table being provided with a raised annular peripheral bead, substantially as hereinafter set forth.

20 The accompanying drawing illustrates a perspective view of a nebulizer-support made in accordance with my design.

In said drawing, A designates an ornamental base; B, the columnar upright cylindrical tank 25 mounted thereon; C, the circular table mounted on said tank and having a raised annular inwardly-curved bead D and a central raised annular flange E. The said base is provided

with feet which resemble the paws of an animal and with representations of vegetation 30 extending up therefrom. Midway between each two feet is a heart-shaped border, in relief, extending down below the proximate parts of the base and inclosing a representation of foliage. Those parts of the base between the feet and heart-shaped figures are 35 narrow, with a decoratively-roughened surface, vertical corrugations at intervals, and a round bead at the upper and lower edges.

The nebulizer-support made in accordance 40 with the said design is exceedingly ornamental and intended for use where it will be continually seen and admired.

Having described our invention, what we claim as new, and desire to secure by Letters 45 Patent, is—

The ornamental design for a nebulizer-support as herein shown and described.

In testimony whereof we affix our signatures in presence of two witnesses.

WM. BOEKEL.
JULIUS BOEKEL.
